UNITED STATES PATENT OFFICE.

LOUIS V. ARONSON, OF NEWARK, NEW JERSEY.

DESIGN FOR AN ELECTRIC CANDELIER.

Application filed August 26, 1926. Serial No. 18,873. Term of patent 3½ years.

To all whom it may concern:

Be it known that I, LOUIS V. ARONSON, a citizen of the United States, residing at Newark, in the county of Essex and State of New Jersey, have invented a new, original, and ornamental Design for an Electric Candelier, of which the following is a specification, reference being had to the ac-

companying drawing, forming part thereof.

The figure is a perspective view of an electric candelier, showing my new design.

I claim:

The ornamental design for an electric candelier, as shown.

LOUIS V. ARONSON.
